UNITED STATES PATENT OFFICE.

JABEZ E. RAY, OF TOLEDO, OHIO, ASSIGNOR, BY MESNE ASSIGNMENTS,
TO THE POSTAL PRINTING & SUPPLY COMPANY, A CORPORATION
OF OHIO.

MACHINE FOR THE MANUFACTURE OF FACING-SLIPS FOR THE POSTAL SERVICE.

No. 821,122.

Specification of Letters Patent.

Patented May 22, 1906.

Application filed September 15, 1902. Serial No. 123,380.

To all whom it may concern:

Be it known that I, JABEZ E. RAY, a citizen of the United States, residing at Toledo, in the county of Lucas and State of Ohio, have invented certain new and useful Improvements in Machines for the Manufacture of Facing-Slips for the Postal Service; and I do declare the following to be a full, clear, and exact description of the invention, such as will enable others skilled in the art to which it appertains to make and use the same, reference being had to the accompanying drawings, and to the characters of reference marked thereon, which form a part of this specification.

In the railway postal service each mail-pouch or parcel of mail-matter transferred from one line or route to another carries what is known as a "facing-slip." These slips bear the name of the route from which it came, together with the number of the train, the name of the mail-clerk from whose charge it came, the date, and the name of the route and the number of the train to which it is to be transferred. These slips when used upon pouches or sacks are folded in such manner as to slip into the metal "ties" or holders which accompany each pouch or sack, and the slips must be so folded that the destination of the pouch or sack is exposed in the tie or holder. It will be seen that no two of the facing-slips used by a railway postal clerk are alike and that for this reason much care, time, and labor are necessary in the preparation by the postal clerks of the facing-slips to be used upon each one of their trips. Usually one or two lines of the facing-slip are printed, and the remainder of the slip is filled out with inked hand-stamps or with writing, or both.

My invention relates to means for overcoming largely the objectionable features of the time, labor, and care necessary in the preparation of these facing-slips; and its object is to provide a machine for the manufacture of facing-slips which are printed and folded complete and arranged in their proper order ready for use.

It is obvious that if in the printing of these facing-slips a separate type-plate were to be employed for printing all the lines of each separate slip the bulk and weight of the

type-plates would be so great as to practically forbid their use.

A further object of my invention is to overcome this difficulty by providing in my machine two separate coöperating printing mechanisms, one of which shall print those lines which are uniform—as, for instance, the date, the name of the route and the number of the train, and the name of the postal clerk from whom the slip came—the other printing mechanism being designed to print in succession from a series of small light type-plates the lines of the slips which are of a variable character—such, for instance, as the name of the route and the number of the train to which the slip is to be transferred.

I attain these objects by means of the mechanism, devices, and arrangement of parts hereinafter described and shown, and illustrated in the accompanying drawings, in which—

Figure 1 is a side elevation of my machine forward of line y y ; Fig. 2, a like elevation of the opposite side of my machine; Fig. 3, a central vertical longitudinal sectional elevation of my machine backwardly from the tension-roller 3, hereinafter referred to; Fig. 4, a side elevation of the rear end of my machine seen from the side opposite to that shown in Fig. 3; Fig. 5, a front end elevation of my machine; Fig. 6, a top plan view of my machine back of the tension-roller, hereinafter referred to; Fig. 7, a transverse sectional elevation taken on line x ' x '; Fig. 8, a diagrammatical view of the type-plate-handling mechanism, hereinafter referred to; Fig. 9, a cross-sectional elevation taken on line x ' x ''; Fig. 3; Fig. 10, a central vertical longitudinal sectional elevation of the folding and packing mechanism, hereinafter referred to, on an enlarged scale; Fig. 11, a side elevation of the plate 133, hereinafter referred to, showing the channels and bridges by which the traveling frame 130, hereinafter referred to, is caused to move to and fro in different horizontal planes; Fig. 12, a side elevation of the upper end of the slip-box, hereinafter referred to, together with the latch-hook 150, disengaged from the frame of the machine to permit the removal of the slip-box. Figs. 13, 14, 15, and 16 are side elevations, partly in section, of the mechanism for carrying and

depositing the folded printed slips, herein-after referred to, said mechanism being shown in different positions.

Like letters and numerals of reference indicate like parts throughout the drawings.

In the drawings, A is a stout elongated rectangular frame, upon the top of which is supported a table B. Journaled in the sides of the frame is a driving-shaft C, which carries a suitable driving-pulley. (Not shown in the drawings.)

D is a shaft journaled in one side of the frame and driven by a miter gear-wheel E, which engages a corresponding gear-wheel 15 on the driving-shaft.

1 is a roll of paper from which the facing-slips are to be manufactured and which corresponds in width with the length of the slips. This roll is mounted on a spindle 2, 20 removably supported in hooks, as shown, and passes over a tension-roller 3, journaled in frame 3^a, bolted on the frame of the machine, and beneath a tension-plate 4, which is pressed normally toward the tension-roller 25 by means of springs 5. These are adjustably tensioned by means of screws 6.

From the tension device 3 4 the paper leads between feed-rollers 7 7. These rollers are driven by a grip-pawl 7^a, which when moving in one direction engages the rim of a friction-wheel 7^b; fixed on the shaft 7^c of the bottom feed-roller. Loose on the end of this shaft is a segmental gear-wheel 7^d, to an arm of which 7^e is pivotally secured the pawl 7^a. 35 The gear-wheel 7^d is engaged by a horizontal toothed rack 7^f, supported at the side of the frame of the machine in guide-blocks 7^g. The rack is pivotally connected with one end of a connecting-rod 7^h, the other end of which is 40 connected with a crank 7ⁱ on the end of the driving-shaft. 8 8 are tension-springs which press one of the feed-rolls against the other, the stress of which springs is governed by means of tension-screws 9. By means of the 45 gearing here described the rack-bar 7^f is reciprocated, and through the grip-pawl 7^a and the friction-wheel 7^b the feed-rolls are given intermittent forward rotation between the printing operations, hereinafter to be described.

In its passage from the tension-roll 3 to the feed-rolls 7 the paper passes over a platen 10, secured upon the table. Above the platen is a type-bar holder adapted to removably receive and hold a plurality of type-bars 12. (See Fig. 3.) The type-bar holder 11 is pivotally supported in a frame 13, which is movable vertically in guides or ways 14, bolted to the under side of the table. 15 is a cam-60 rod pivotally connected at one end to the frame 13 and having at its other end a cam-roller 16, which rides upon and is actuated by a cam 17 on the shaft D. The type-bar holder 11 has at each end slotted arms 11^a. 65 Through the slots of these arms passes a sta-

tionary rod 11^b, secured to the frame of the machine. When the part 11 is lifted by the cam 17, the slotted arms which engage the stationary rod cause the type-bar holder to turn upon its pivots with the faces of the type-bars turned upwardly, so that they are now exposed to the action of the inking-rollers 11^c, which are caused at each impression to move from the distributing inking-rollers 11^d over the inking-plate 11^e, in which is an opening 11^f, through which the face of the types is presented to the inking-rollers 11^c. The frame in which the inking-rollers 11^c are journaled is mounted upon and between the extremities of a pair of arms 18, extending 70 down through the table and rigidly connected with a shaft 19, which is journaled in bearings upon the under side of the table. The arms 18 are actuated by a cam-rod 20, pivotally connected at its upper end with one of the arms 18 and carrying at its lower end a cam-roller 21, which rides upon cam 22 on the shaft D. When after each impression the type-bars 12 are turned upwardly and presented through the opening 11^f, the cam 22 and its connections cause the arms 18 to swing downwardly, carrying with them the inking-rollers 11^c, which now traverse the exposed upturned faces of the type-bar and then return to the position shown in Fig. 3. 95

23 is a type-wheel mounted upon and secured to a shaft 24, which is journaled in standards or plates 25, which spring from the top of and are rigidly connected with the frame of the machine. On one end of the shaft 24 is fixed a ratchet-wheel 26, which is intermittently actuated by a pawl 27, pivoted on one end of an arm 28, the other end of which is journaled loosely on the shaft 24. The arm is given motion by means of a cam-rod 29, pivotally and adjustably connected at its upper end to the arm 28 and having at its lower end a cam-roller 30, which rides upon a cam 31, secured to the driving-shaft C. 100

32 is a platen vertically movable in guides or ways rigidly connected with the frame of the machine. A downwardly-projecting arm of the platen carries at bottom a roller 33, which rides upon a cam-wheel 34, fixed on shaft D. The face of this cam-wheel is 115 broader than the face of the roller, and the eccentric or projecting portion 35 of the cam-face extends only part way across the face of the cam. The cam may be shifted into inoperative position by means of a shifter 36, operated by hand-lever 36^a, so that the roller will not lie in the path of the eccentric, but will roll without vertical movement upon the circular portion of the face of the cam-wheel. The cams 31 and 34 are so arranged on their shafts and in relation to each other that the platen 32 is lifted during the pause of the type-wheel 23 between the movements of the pawl 27. 120

37 is a rack or trough for holding the type- 125

plates which are to be fed into the type-wheel 23, and 38 is a similar trough or rack for the reception of the type-plates after they are discharged from the type-wheel. Across the periphery of the type-wheel 23 are equidistant rectangular recesses or grooves, each of which exactly conforms to and is adapted to receive and to hold one of the type-plates. For illustration these type-plates may be in practice four inches long, seven-eighths of an inch wide, and one-sixth of an inch thick. These type-plates are shown in position in their racks, as at 40, in Figs. 1 and 2. The series of type-plates are fed forwardly in rack 37 by means of a follower 41, provided with a divided nut 41^a. Only the lower half of this nut is threaded. The lower half is pivoted to the upper half. The two parts are held in closed position by a catch 41^b, which is adapted and arranged to be tripped by a roller 41^c, mounted on an arm of the catch. This roller at the end of the forward movement of the follower rides upon an inclined plane 41^d. The lift of the roller and the arm 25 disengages the catch, throwing the threaded portion of the nut out of engagement with the feed-screw 42, by which the follower is actuated, thus causing the follower to stop at the proper point in its travel. The feed-screw is journaled beneath the rack 37 and has secured to its outer end a ratchet-wheel 43. This ratchet-wheel and the screw are intermittently rotated by means of pinion 44, having rigidly connected with it an arm 45, which carries at its outer extremity a pawl 46, which engages the ratchet 43. The pinion is loosely journaled upon the screw 42 near its end. The teeth of the pinion 44 are engaged by a rack-bar 47, which slides in 40 guide 47^a, pivotally mounted upon the outer end of the feed-screw. The rack-bar is secured to and forms a continuation of a connecting-rod 48, which is pivotally connected with and longitudinally adjustable, as at 49, upon crank-arm 50. This crank is secured to the extremity of shaft 51, journaled in the frame of the machine, which shaft has a miter gear-wheel 52, driven by a corresponding gear-wheel 53 on the driving-shaft. (See 45 Figs. 2 and 7.)

54 is a lever fulcrumed upon shaft 55. (See Fig. 8.) At the top of this lever is a carrier 56, having a spring-jaw 56^a. The mouth of the carrier is toward and in line 55 with the advancing type-plates in the rack 37. The lever 54 at its lower end carries a roller 57, which is engaged by a cam 58 on the shaft D, which imparts motion to the lever and carrier. The movement of the lever and of the cam 58, the lever 54, and the carrier 56 are in harmony, so that at each rotation of the screw a type-plate is pressed flatwise into the jaws of the carrier. The cam 58 now swings the upper end of the 60 lever with the carrier, so that the type-plate

is brought into line with the end of one of the recesses 39 in the type-wheel. A finger or plunger 59 slides transversely to the type-wheel and in line with and in such manner as to impinge upon the end of the type-bar, 70 which is forced from the holder into its recess in the face of the type-wheel. This finger or plunger is supported on a rod 60, supported at each end on brackets secured to the frame of the machine. The finger or 75 plunger 59 is pivotally connected, as at 61, with and is actuated by a connecting-rod 62, which at its outer end is pivotally connected, as at 63, with the upper end of the lever 64, fulcrumed, as at 65, on the frame 80 of the machine. (See Fig. 7.) The lever 64 has an extended arm 66, which carries at its outer extremity a roller 67, which rides upon a cam 68 on shaft D. At each end of the type-wheel is a plate having an inwardly-turned flange 69, formed in the arc of a circle and overlapping slightly the circumferential face of the type-wheel. These flanges form guides which retain the type-plates in place until they reach the point 90 where they are to be removed. (See Fig. 3.) 70 is another finger or plunger like the finger or plunger 59. This member slides on a fixed rod 71 and is connected, as at 72, with one end of a connecting-rod 73, which at its 95 other end is pivotally connected, as at 74, with the upper end of a lever 75, fulcrumed, as at 76, on a bracket secured to the side frame. (See Fig. 7.) A connecting-rod 77 is pivotally connected at one end, as at 78, 100 to the lever 75, and at its other end is pivotally connected, as at 79, to an arm 80, which is rigidly connected to the shaft which forms fulcrum 65. The throw of the lever 64 when it is actuated by the cam 68 causes 105 the finger or plunger 59 to push the type-plate edgewise out of the holder into one of the recesses 39 in the face of the type-wheel. The type-wheel turns step by step until the type-plates are in succession presented to 110 the movable platen 32 and are printed from and are brought opposite to the end of the trough or rack 38. The two levers 64 and 75 move in unison in opposite directions. 115 When a type-plate is pushed into the type-wheel, the plunger or finger 70 at the same instant pushes a type-plate out of the wheel onto a stationary rack or shelf 81, from whence the type-plate is picked up by a carrier 82, having jaws like the carrier 56. 120

125 Since the type-plates, while they are in the type-wheel, are given a half-turn and are discharged from the type-wheel with their faces reversed, it is necessary to give the type-plate another half-turn in order that the series of plates when taken from the machine shall preserve their original order, thus dispensing with the necessity for rearranging the type-plates by hand. This is accomplished as follows: The carrier 82 is pivotally 130

mounted, as at 82^a, (see Figs. 6 and 8,) upon the end of arms 83, pivotally connected at bottom with the frame of the machine. These arms are connected by means of a connecting-rod 84 with the lever 54, upon which swings the carrier 56. Projecting laterally from the ends of the carrier 82 are pins 85, which project through irregular slots 86 in the sides of the trough or rack 38. (See Fig. 8.) When the arm 83 is swung, the pins 85, guided by the slots 86, cause the carrier to describe half a revolution on the pivots 82^a, so that the type-plate is reversed and placed right side up in rack 38 and in regular order to be again placed in rack 37 when required.

In order that the type-plates as they pass from one trough or rack into the type-wheel and into the other trough or rack may preserve their upright position, I provide spring-plates 87, which press upon the top margins of the type-plates at the ends of the racks and which hold the plates erect and keep them from falling flat. The carrier delivers the plate flatwise, and the upper and lower margins of the plate are clasped between the bottom of the trough or rack and the spring-plate and held against returning with the receding carrier. As the successive plates are delivered by the carrier to the clasp of the spring the series of plates moves onward step by step in rack 38.

The inking-roller 11^c, heretofore referred to, is given motion by a pulley on its shaft, over which pulley passes a belt, which passes over and is driven by shaft 51. The inking-roller 11^c engages a train of rollers, the last roller of which train rolls upon and inks the type-faces of the type-bars in the recesses 39 as the type-wheel carries these type-plates toward the platen 32. (See Fig. 3 and dotted lines in Fig. 1.)

The ribbon of paper from the roll having passed between the platen 32 and the type-plate and having received its second impression passes onto a drier. This drier may be of any preferred form. I have shown by way of illustration a plate 88, over and in contact with which the paper travels and under which is a perforated gas-pipe 89, which supplies a flame to the bottom of the plate.

Before folding the printed slips and depositing them in the order in which they will be required for use it is necessary to sever the slips from the ribbon of paper. This is accomplished by means of a vertically-swinging knife 90, which works through a slot 91 in the table. The knife is secured to a lever 92, fulcrumed, as at 93, and is held normally elevated by spring 94. The lever 92 is connected with the top of a connecting-rod 95, which at bottom is pivotally connected with one end of a lever 96, the other end of which lever carries a roller 97, which rides upon a

cam 98 on the driving-shaft. The cam 98 moving in unison with the other mechanisms of the machine causes the knife 90 to slice off the printed slips at the proper points.

As the paper leaves the feed-rolls it passes and is pushed forward upon the top of the table under the knife and beneath a flat plate 99, secured to the top of a carriage 100. This carriage is adapted to be moved manually upon guides or ways 101 on the top of the frame of the machine, but is normally stationary. The severed slips of paper as they are pushed forward emerge from beneath the plate 99 and pass edgewise between two flat parallel blades 102. Each of these blades at its outer end is secured to a head or shank 103, having a shaft extension 104, which shaft revolves and slides in a journal 105, fixed on the carriage 100. The two blades are given longitudinal motion toward and away from each other by means of the mechanism now to be described. At the outer end of each of the shafts 104 is a collar 106, to which is pivotally connected, as at 107, (see Fig. 9,) one end of a connecting-rod 108. The other end of this rod is connected with a lever 109, fulcrumed, as at 109^a, on carriage 100. The short curved extremity of the lever 109 carries a roller 110, which lies in the path of inclined planes 112, formed by the upturned flanges of plates 113, which are adjustably secured to the extremities of a cross-bar 114, secured to the top of standards 115, which spring upwardly from the opposite sides of the grid-frame 116. This frame slides upon grooves or ways 117 (see Fig. 9) on the carriage 100. Projecting down from the frame or carriage 100 are two arms or brackets 118, in the lower end of which is journaled a rock-shaft 119, carrying at its end a crank 119^a. (See Fig. 4.) This crank is engaged by a connecting-rod 120, as indicated by dotted lines in Fig. 3. This connecting-rod engages at its opposite end a crank 121 on the driving-shaft. Secured to the rock-shaft 119 is an upwardly-projecting arm 122, which at its top is pivotally connected with one end of a connecting-rod 123, which at its other end is pivotally connected with the grid-frame 116. The inward swing of levers 109 compresses a spring in each of the dash-pots 124, secured to the carriage 100. When the inclined planes 112 cause the rollers 110 to swing outwardly and the long arms of the levers 109 to swing inwardly, a pawl 125 engages a notch 126 on the lever and for the time being holds the lever stationary with the two blades 102 overlapping each other. The shanks or heads 103, which carry the blades 102, have upon their adjacent ends inclined portions 127, (see Fig. 9,) against which the ends of the blades abut when they are moved into overlapping position. The inclined planes 127, upon which the ends of the blades slide, cause the blades

125 overlap each other. The shanks or heads 103, which carry the blades 102, have upon their adjacent ends inclined portions 127, (see Fig. 9,) against which the ends of the blades abut when they are moved into overlapping position. The inclined planes 127, upon which the ends of the blades slide, cause the blades 130

to move laterally toward each other and to pinch between their flat adjacent sides the slip of paper which the feed-rolls have fed between the blades. The movement of the two blades asunder is caused by the release of the pawl 125 from the lever 109, which permits the springs in the dash-pots 124 to throw the levers 109 outwardly, pulling the blades lengthwise away from each other. The release of the pawl 125 is effected by means of a projection (not shown in the drawings) upon frame 116, which on the return of the frame comes in contact with and trips the pawl.

15 The two blades are given rotary motion by means of pinions 128 on the shanks or heads of the blades, which pinions when the blades are in overlapping position lie in the path of rack-bars 129, adjustably secured, as at 129^a, to the grid-frame 116 and movable therewith. When the grid-frame moves toward the blades, the teeth of the rack-bars passing under and engaging the pinions cause the blades, with a severed slip clamped between them, to describe two complete revolutions, pulling the paper out from between the plate 99 and the floor of the frame 100 and wrapping the paper around the blades in flat folds in such manner that the printed portion of 30 the facing-slip which is to be exposed when in use will be turned downward.

130 is a horizontal frame supported on forward rollers 131 and rear rollers 131^a, journaled on the ends of cross-bars on the frame. 35 These rollers move in races 132 in the inner sides of side plates 133, which are rigidly secured to the frame 100. The cross-bars which carry the rollers 131^a pass between lugs 134, which project upwardly from the frame 116 and form guides between which the ends of the cross-bars which carry the rollers 131^a move vertically. As the frame 116 is moved to and fro the lugs 134 engage and move the frame 130. The races 132 are 40 irregular and guide the rollers 131 and 131^a, so that the shafts, which are a part of the frame 130, have a vertical movement between the lugs 134 as well as a longitudinal horizontal motion. The races 132 at their 45 part nearest the rear end of the machine have upper and lower connected tracks. The rollers 131 in moving away from the folding-blades traverse the lower track, and moving forward the rollers 131 and 131^a traverse the 50 upper track. This is effected by means of bridges 135, which are pivoted at one side and which are lifted by the rollers 131 as they move backwardly and pass under the bridges, but which lie flat, forming a support over 55 which the rollers travel into the upper track on their return. Thus it will be seen the frame 130 and its appendages move away from the folding-blades in a plane below the plane of their return movement.

65 From the forward part of the frame 130

projects a series of horizontal fingers 136, which are rigidly connected with the frame. The fingers are curved upwardly at front and at rear and have vertical shoulders, as shown in Fig. 3. Secured to the under side of the frame beneath each of the fingers 136 is a spring 137, which conforms to and presses normally upwardly against the fingers 136. Adjustably secured to the side plate 133 is a rear stop 138 and a forward stop 138^a, which lie in the path of a tripping-lever 139, fulcrumed on the frame 130. There are two of these levers disposed at opposite sides of the frame 130, and they are connected by a cross tie-rod 139^a. This rod rests upon the top of the springs 137, and when the tripping-levers come in contact with the stops 138 one end of the levers is thrown upwardly, while the opposite ends of the levers are thrown downwardly, thus by means of the cross-rod 139^a 85 pressing the forward ends of the springs down and forming open jaws between the extremities of the fingers and the springs. When the tripping-lever comes in contact with the forward stop 138^a, the lever is swung in the 90 opposite direction, allowing the cross-rods and the springs to move upwardly. At this point the overlapping blades with the folded slips between them rest between the fingers and springs.

140 is a box removably secured beneath the table to the bracket 118. The box in transverse area is slightly larger than the folded slip, has an open upturned mouth, and a sliding bottom 140^a, pressed upwardly and controlled by a spiral spring 140^b, surrounding the lifting-rod 140^c, secured at top to the sliding bottom.

When the springs and fingers which clasp the folded slip move away from the folding-blades, the two pairs of rollers 131 and 131^a travel downwardly on the inclined portions of the lower track of race 132, so that the folded slip passes directly over the upturned mouth of the box 140. At the top of the rear side of the box are lugs or short fingers 141, (shown in Fig. 6 and in dotted lines in Fig. 3,) which project upwardly between the pairs of springs and fingers and which as the fingers and springs continue their backward motion 110 catch the edge of the folded slip directly over the mouth of the box and force it edgewise from between the fingers and springs.

142 is a cross-bar, the ends of which rest in and slide upon the ways 117. Projecting backwardly from this bar is a series of fingers 143, which fingers move to and fro between the lugs 141, just behind and in line with the fingers and springs 136 and 137, and which when the folded slip is released, as above described, slide upon the top of the slip and force it downwardly into the upturned mouth of the box. The bar 142, with its fingers, is actuated by means of a pair of connecting-rods 144, pivoted at one end to the cross- 125

bar 142, (see Fig. 3,) and having at their opposite ends elongated links 145, which engage loosely the extremities of a cross-shaft 146, which is secured to the underside of the frame 5 116.

147 is a series of forwardly-projecting fingers secured to the rear cross-bar of frame 116 in-line with the fingers 143.

When the frame 116 is at the end of its 10 backward stroke, the fingers 143 rest across the top of the box 140, holding the folded slips down in the box against the upward pressure of the spring 140^b. When the frame 116 moves forwardly or toward the 15 forward end of the machine, the fingers 143 remain motionless, while the shaft 146 moves forward in the open links of the connecting-rods 144, which actuate the fingers 143, and when the fingers 147 slide over the top of the 20 box and hold the slips in place the shaft 146 engages the ends of the links and pushes the series of fingers 143 back to the end of its backward stroke. Thus either the fingers 143 or 147 rest constantly on the top of the 25 box between the lugs 141, except at the moment when the paper is deposited in the top of the box, at which moment there is enough space between the adjacent ends of the two sets of fingers to not interfere with the movement of the fingers and springs 136 and 137 30 and to permit the deposit of the slip, as above described.

The rectangular box in which the slips are deposited is provided with and supported by 35 hooks 148, which engage a stout rod 149, secured to the side arms of the bracket 118. The box also has a latch-hook 150, which engages the under side of a lug on the bottom of carriage 100, as shown in Fig. 3. Upon 40 the box slides a sleeve 151, to which is pivotally secured an arm 152, which carries a series of fingers 153, which are adapted to swing between the fingers 147. The sleeve may be slipped upwardly far enough to permit the 45 fingers 153 to swing by the aid of spring 154 over the top of the box to prevent the escape of the deposited folded slips. When the sleeve is slipped upwardly, it strikes and disengages the latch 150, permitting the rod and 50 box to be swung on 148 149 and to be lifted off and to be taken out of the machine.

To empty the box, the arm 152 and the fingers 153 are swung out of the way, and the spring 140^b forces the column of slips out 55 from the box. It is now only necessary to reverse the column of slips and tie it in a convenient package, when the printed faces of the printed slips appear uppermost in the order in which they are to be used.

60 The operation of my machine is as follows: Assuming that the parts are assembled as above described, that the carriage 100 carrying its movable frames 116 and 130 is suitably secured in place, that the paper from 65 the roll 1 is threaded, as above described, be-

tween the tension-roll and tension-plate and between the feed-rolls and beneath the knife, and that the inking mechanisms are properly supplied with ink. Assuming, also, that the series of facing-slips to be prepared is for a 70

railway postal clerk's one day run and that upon each slip is to be printed, first, the name of the route and the number of the train from which the slip proceeds; second, the date; third, the name of the postal clerk 75

from whose charge it came, and, fourth, the name of the route and the number of the train to which the slip is to be transferred. Now type-bars 12 bearing the first, second, and third of the above items are secured in the 80

type-bar holder 11 and a series of type-bars bearing the fourth of the above items is placed in position in the rack 37 with the screw-fed follower resting against the last plate in the series of type-plates, the divided 85

nut 41^a, however, being left open at the start. Motion is now given to the driving-shaft, and the paper begins to move in the machine. When that portion of the strip of paper which 90

has passed beneath and has received impressions from the type-bars 12 arrives above platen 32 and beneath the opposing type-plate 40, which is the first of the series of type-plates and which has been fed into the type-wheel, as above described, and 95

brought into position, the feed-screw 42 is manually engaged with the follower by closing the divided nut 41^a and the type-wheel is thrown into operative engagement with the driving mechanism by means of the 100

shifter 36. Now the slips which have been printed by the type-bars 12 as they arrive above the platen 32 receive successively and in proper order impressions from the type- 105

plates 40 as they are one by one presented to the strip of paper and to the action of the platen. When the type-wheel moving step by step has received at one side all of the type-plates of the series and has discharged 110

the plates at the opposite side into rack 38, 115 each of the plates having been printed from in its order, the series of plates may be transferred bodily back to the rack 37 in their original order. Upon changing the date type- 120

bar 12 the operation may be repeated, and the series of slips necessary for the next trip 125 may be printed. In practice these operations are repeated with a change of the date-bar for each run for a month, a month's supply being furnished during the then current

month for the next succeeding month. From the second printing operation the strip of paper moves on over the drying-plate 88 between the feed-rolls, beneath the knife, and 130

between the plates 99 100. The severed slip of paper as it emerges from beneath the plate 99 is clamped between the two blades 102. Now the frame 116 moves forward, carrying with it the rack-bars 129, which engage the 135

pinions on the shanks of the blades, causing

the blades to revolve and to pull the paper out from beneath the plate 99 and to fold the paper around the blades in flat folds. The 5 spring-jaws 136, 137 now clasp the folded paper, and at the same instant the pawl 125 is disengaged from the lever 109, and the blades are by the action of the levers 109 and the spring and the dash-pots 124 pulled lengthwise and in opposite directions out from the 10 folds in the paper. The jaws carrying the folded slip move away from the folding-blades and, as above described, deposit the folded slip at the mouth of the box 140. As the jaw-carrying frame moves to and fro the 15 folded slips are held in place and are pressed into the box by the reciprocating fingers 143 and 147. This operation is repeated until the entire series is printed, when the box is removed, as above described, and the bundle 20 of slips is ejected by the spring to be caught and tied together for use, as may be required. In case the slips are not to be folded—as, for 25 instance, when the slips are to be used in labeling letter-packages instead of pouches or sacks—the carriage 100, with its burden, is moved back upon its track out of the way, and the slips now fall flatwise from beneath the plate 99 without folding.

While I have fully described the construction and operation of my folding mechanism, I have not in this specification made claims therefor, for the reason that this part of my invention is to be made the subject of a separate application for a patent.

Having described my invention, what I claim, and desire to secure by Letters Patent, is—

1. In a machine of the described class, two coöperating registering printing mechanisms, 40 one of said printing mechanisms being adapted and arranged to repeat its impressions uniformly, the other of said printing mechanisms being adapted and arranged to change its impression at each succeeding imprint, 45 and means for intermittently feeding paper to said printing mechanisms successively in harmony with their movement.

2. In a machine of the described class, means for printing a series of slips the subject-matter of which is, in part, uniform, and, 50 in part, varied with each succeeding slip, said means comprising a printing mechanism for the constant matter, a printing mechanism for the variable matter, the imprint of the latter printing mechanism registering with that of the first-mentioned printing mechanism, means for actuating said two printing mechanisms in harmony with each other, and means for feeding paper successively to said 55 two printing mechanisms in harmony with their movement.

3. In a machine of the described class, means for printing upon a series of slips matter which is uniform throughout the series, 60 means for printing upon said slips matter

which varies throughout the series, and means for folding said slips with the variable matter exposed.

4. In a machine of the described class, a roll-holder for a paper-roll, a printing mechanism which prints uniform matter at regular intervals upon said paper, a printing mechanism which prints varying matter at like regular intervals upon said paper, the impressions of said printing mechanisms being successive but registering with each other, means for feeding the paper through said printing mechanisms in harmony with their movement, and means for severing the paper at regular intervals between its printed portions.

5. In a machine of the described class, a roll-holder for a paper-roll, means for printing upon such paper, at regular intervals, matter which is uniform, means for printing 85 upon such paper, at like intervals, matter which constantly varies, means for feeding paper from such roll in harmony with the movement of the printing mechanisms, means for severing the paper between the printed 90 portions thereof, and means for folding the paper with the variable matter printed thereon exposed.

6. In a machine of the described class, two coöperating printing mechanisms, means in 95 one of said mechanisms for printing uniform matter, means in the other of said printing mechanisms for printing variable matter, a drying device, a cutter, and a folder, combined with a paper-roll holder, means for presenting a strip of paper from a roll on said holder to the successive action of the printing mechanisms the drier the cutter and the folder.

7. In a machine of the described class, a 105 printing mechanism for printing upon a series of slips matter which is uniform throughout the series, a printing mechanism for printing upon said slips matter which varies throughout the series, means for folding said 110 slips with the variable matter exposed, and means for assembling said folded slips in their proper order in a suitable receptacle.

8. In a machine of the described class, a cylinder, a series of type-plates bearing 115 constantly-changing matter, means for operatively securing said type-plates upon said cylinder, means for imparting intermittent rotation to said cylinder, means for feeding to said cylinder a series of type-plates, means 120 for printing from said type-plates in succession, and means for removing said type-plates successively from said cylinder combined with a coöperating printing mechanism adapted to print uniform matter which registers 125 with said changing matter.

9. In a machine of the described class, a cylinder, means for detachably securing type-plates in operative position upon the cylinder, two holders adapted to receive a series of 130

type-plates; means for transferring said type-plates successively from one holder to the cylinder, means for removing said type-plates successively from the cylinder to the other holder, said latter means including devices for giving each type-plate a half-turn during its passage from the cylinder to the latter holder whereby the printing-face of the type-plates will be disposed in the latter holder in their original relative and successive positions without rearrangement.

10. In a machine of the described class, a paper-roll holder, two coöperating registering printing mechanisms, means for presenting a strip of paper from a roll on said roll-holder to the successive action of said printing mechanisms, means in one of said printing mechanisms for printing upon said paper, at regular intervals, uniform matter, and means in the other printing mechanism for printing variable matter on said paper, at like intervals, and in registration with the imprint of the first-mentioned printing mechanism, said latter means comprising a cylinder, means for operatively securing type-plates upon said cylinder, a platen, means for inking the type-plates, two holders for a series of type-plates, means for removing said type-plates successively from one holder to the cylinder, and means for removing said type-plates successively from the cylinder to the other holder.

11. In a machine of the described class, a cylinder having upon its face spaced recesses for the reception of type-plates, a platen, an

inking mechanism for such type-plates, two holders for a series of type-plates, a feed-screw, a follower in one of said type-plate holders controlled by said feed-screw, means for successively removing a series of type-plates from said latter holder to the recesses in said cylinder, means for removing said type-plates successively from said cylinder to said other type-plate holder, and means for imparting harmonious intermittent movement to the feed-screw the cylinder the platen the inking mechanism and the devices for moving the type-plates to and from the cylinder.

12. In a machine of the described class, a holder 11 for type-bars, means for removably securing type-bars therein, pivotal supports for said holder, a platen, means for reciprocating the holder to and from the platen, means for inverting the holder upon its pivotal support after each impression, and an inking mechanism adapted to ink the type-bar faces at each inversion of the holder, combined with a coöperating printing mechanism which registers with the imprint of the first-mentioned printing mechanism, and is adapted and arranged to change the impression at each succeeding imprint, and means for intermittently feeding the paper-successively to said two printing mechanisms.

In testimony whereof I affix my signature in presence of two witnesses.

JABEZ E. RAY.
